CLAIM

The ornamental design for a medical pump, as shown and described.

DESCRIPTION

FIG. 1 is a front, top, and right side perspective view of the medical pump, showing our new design;

FIG. 2 is a rear, top and right side perspective view thereof;

FIG. 3 is a top plan view thereof;

FIG. 4 is a bottom plan view thereof;

FIG. 5 is a front side elevational view thereof;

FIG. 6 is a rear side elevational view thereof;

FIG. 7 is a right side elevational view thereof; and,

FIG. 8 is a left side elevational view thereof.

The ornamental design which is claimed is shown in solid lines in the drawings. The broken lines immediately adjacent the shaded areas represent the bounds of the claimed design, while all other broken lines are directed to portions of the article excluded from the claim. The broken lines form no part of the claimed design.
